ELECTRIC DISCHARGE DEVICE

Original Filed March 2, 1929

FIG.1

FIG.2

CHARLES SPAETH
INVENTOR

BY

Dannenreich

ATTORNEY

UNITED STATES PATENT OFFICE

CHARLES SPAETH, OF FLUSHING, NEW YORK

ELECTRIC DISCHARGE DEVICE

Original application filed March 2, 1929, Serial No. 343,873. Divided and this application filed December 3, 1929. Serial No. 411,277. Renewed January 27, 1932.

This is a division of my copending application Serial No. 343,873, filed March 2, 1929.

The invention relates to electrical discharge devices, particularly to devices used for purposes of illumination.

It is an object of the present invention to provide an electrical discharge tube which is capable of producing a very efficient white light.

Another object is to provide an electrical discharge illuminating tube wherein the color characteristics of the emitted light may readily be modified in a predetermined manner.

A further object is the provision of an electrical discharge tube operating at high efficiency and adapted to produce a concentrated brilliant light emission approximating sunlight.

In accordance with my invention a radiant energy emitting discharge device is constructed having a filling of gas at reduced pressure and a plurality of electrodes for conducting an electrical discharge therethrough. For modifying the light emission from the device, auxiliary means are arranged to add to the gas filling in the desired amounts an agent for modifying the radiation spectrum. This auxiliary device is preferably in the form of a mercury reservoir provided with means for liberating mercury vapor. In place of mercury other elements or combinations of elements may be used, for example, cadmium, thallium, sodium or calcium, depending on the spectrum modification desired.

A preferred form of my invention for illuminating purposes comprises an envelope containing an atmosphere of rare gas, such as neon, and having a reservoir of mercury. Electrodes are provided for passing a discharge directly through the rare gas and another electrode for causing a discharge to be passed to the mercury in order to vaporize it. In order to secure the desired characteristics of illumination from the device, means, such as resistances, inductances or capacitances, may be provided for controlling the relative intensities of the discharges.

For liberating the mercury suitable heating means may be employed in place of the auxiliary electrode. This heating means may comprise any suitable source of external heat, but preferably is in the form of a heating coil placed adjacent to the mercury reservoir and adapted to be energized by the discharge current.

When it is desired to secure a white light approximating that of sunlight, the filling of the envelope may be of neon gas used in conjunction with a reservoir or other means for supplying an exactly proportioned amount of mercury vapor. It is advisable where the tube is to be operated over a relatively long period of time to maintain the mercury vaporizing means in operation at the correct intensity during the entire operation of the device. It is, however, possible to start the discharge through the rare gas column and then supply the necessary quantity of mercury vapor for a short period of time, after which the device will continue to emit a white light for some time. As operation is continued the mercury is cleaned up, apparently either by condensation, occlusion, absorption or some other phenomena and the light emitted by the device gradually reverts to the characteristic color of the rare gas, which in the case of neon, is substantially red. By operating the mercury vaporizing device at the correct intensity mercury vapor is supplied at the same rate at which it is used up and hence the color of the emitted light remains constant.

For producing other colors of light other monatomic gases, for example, helium, argon, xenon, crypton, may be used with mercury vapor, or one of a mixture of the rare gases of a given characteristic color emission may be used in conjunction with means for liberating a gas or metallic vapor having another color characteristic.

Other objects and advantages and the manner of obtaining them will be made clear in the following specification and accompanying drawing.

In the drawing, Fig. 1 shows a device constructed in accordance with my invention

wherein the modification of the emitted spectrum is obtained by the passage of a discharge to a spectrum modifying material; and in

5 Fig. 2 a lamp suitable for television use is illustrated.

Referring more particularly to the drawing, Fig. 1 illustrates an electrical discharge tube comprising a light transmitting envelope 1 filled with rare gas, such as neon, and having a pair of main discharge electrodes 2 and 3 of any well known type, having the usual lead-in wires. The pressure of the gaseous atmosphere may range anywhere 10 from .1 to 50 millimeters, but I find it preferable to use a pressure in the neighborhood of 6 millimeters. A reservoir for a quantity of mercury 4 is provided in the form of an appendix 5. For energizing the tube the 15 main electrodes 2 and 3 are connected across a suitable source of current 14 by means of conductors 6 and 7. The source 13 may be of either direct or alternating current of a suitably high potential. Connected in series with the conductor 6 is an adjustable resistance 8. For causing discharge to pass 20 to the mercury 4 a connection 9 is made between a lead-in wire 59 sealed through the wall of the reservoir 5 and making contact with the mercury, and the conductor 6. In series with the conductor 9 is an adjustable resistance 10.

In operation a current is caused to pass 25 from the source 13 between the two electrodes 2 and 3, thereby energizing the filling of rare gas and causing it to emit light having certain color characteristics. For example, where the rare gas is neon, the light will be predominantly red. In order to modify 30 these color characteristics the resistance 10 is adjusted so that a discharge passes between the electrode 3 and mercury 4, thereby causing a quantity of the mercury to be vaporized. The mercury vapor diffuses 35 through the gas in the envelope 1, emitting light rays of its characteristic blue color. By properly adjusting the resistance 10 it is possible 40 so to balance the blue rays emitted against the characteristic color of the rare 45 gas as to produce a light emission of any desired color. For example, where the rare gas is neon, a proper adjustment of the resistance 10 may be made to cause the emission 50 of white light, the blue rays of the mercury being complementary to the red rays of the neon. The resistances 8 and 10 serve also as ballast resistances for balancing the negative 55 resistance of the gaseous discharge path. These resistances should therefore never be 60 cut entirely out of circuit as the discharge current would increase to an excessive value. While the mercury reservoir is illustrated as positioned near to one of the main electrodes, it need not necessarily be so located. 65 The device will likewise be operative with

the reservoir at other positions. By placing the reservoir as shown, the impedance of its discharge path is made relatively large.

Fig. 2 illustrates a lamp adapted for television purposes, the lamp comprising a gas filled envelope 40 having a pair of plate electrodes 41 and 42 spaced apart a distance less than the mean free path of the gas in the well-known manner. The envelope is filled with an atmosphere of inert gas, for example, neon and a reservoir 43 containing mercury is provided. In operation, a white light is obtained in the same manner as set forth in connection with Fig. 1. The discharge cannot pass directly between the two plates because of their close spacing and therefore passes around to the outside faces of the plates illuminating them in the well-known manner.

Where neon gas and an auxiliary mercury electrode are used, as set forth, the color may be adjusted from the characteristic neon color, through white, to the characteristic mercury color. The efficiency of tubes constructed in accordance with my invention is extremely high. For example, when using neon gas with mercury vapor to produce a white light, the amount of energy consumed is only about 0.20 watt per spherical candle-power. Because of this relatively high efficiency the amount of heat generated by the device is correspondingly small.

Lamps of this type are substantially silent in operation, especially when direct current is used. They are therefore of great value where a white, silent and relatively cool, high intensity, illuminating source is desired.

It will be obvious to those skilled in the art that the invention is capable of a wide variety of modifications and adaptations and that the present disclosure is intended merely to illustrate its nature without limiting its scope which is set forth in the appended claims.

What is claimed is:

1. In a television lamp, an envelope, a pair of flat electrodes spaced apart a distance less than the mean free path, a filling of rare gas within said envelope, a reservoir containing mercury connected to said envelope, means for passing a discharge between said electrodes, and means for vaporizing said mercury.

2. In a television lamp, means for producing a broad flat field of light, said means comprising a pair of electrodes immersed in an atmosphere of rare gas, and auxiliary means for modifying the color of said light.

3. In a light source, means for producing a broad flat field of light, said means comprising a pair of broad electrodes positioned in an envelope containing an atmosphere of rare gas, and spaced apart a distance less than the mean free path, a reservoir of light modifying material connected to said envelope.

velope, means for passing a discharge between said electrodes, and means for passing a discharge to said mercury.

4. A device in accordance with claim 2,
5 wherein the rare gas comprises neon and the modifying means comprises mercury.

In testimony whereof, I have signed my name to this specification, this 26th day of November 1929.
